DESIGN FOR A NEGLIGEE ENSEMBLE

Ethel Eaton Stricker, New York, N. Y.

Application March 27, 1937, Serial No. 68,422

Term of patent 3½ years

To all whom it may concern:

Be it known that I, Ethel Eaton Stricker, a citizen of the United States of America, residing in Manhattan, county of New York, and State of New York, have invented a new, original, and ornamental Design for a Negligee Ensemble, of which the following is a specification, reference being had to the accompanying drawing, forming part thereof, wherein,

Fig. 3 is an open view of the negligee shown in Figure 1 showing the full over-skirt and the integral undergarment which is visible through the transparent overgarment.

I claim:

The ornamental design for a negligee ensemble, substantially as shown, and described.

ETHEL EATON STRICKER.
